UNITED STATES PATENT OFFICE

2,369,098

BRACKET FOR SUPPORTING VENETIAN
BLINDS

Charles H. Wood, Oakland, Calif.

Application September 13, 1943, Serial No. 502,233

2 Claims. (Cl. 160—178)

The invention relates to a window frame bracket or attachment for supporting within the frame opening the members from which the blind proper is suspended.

An object of the invention is to provide a bracket or attachment of the character described which will permit the entire blind including the suspending members to be quickly inserted and effectively retained in operative position in the frame opening or be easily removed as a complete unit when required.

Another object of the invention is to provide a bracket of the character described which is particularly effective for supporting the tilt rail and permitting its easy insertion in or removal from the frame opening.

A further object is to provide a bracket of the character described which may be formed of non-metallic material.

The invention possesses other objects and features of advantage, some of which, with the foregoing, will be set forth in the following description of the preferred forms of the invention which are illustrated in the drawing accompanying and forming part of the specification. It is to be understood, however, that variations in the showing made by the said drawing and description may be adopted within the scope of the invention as set forth in the claims.

Referring to said drawing:

Figure 1 is a front view of the upper portion of a window frame and blind, showing the supporting members of the latter operatively held in the bracket of my invention.

Figure 2 is a vertical sectional view taken on the line 2—2 of Figure 1.

Figure 3 is a vertical sectional view taken on the line 3—3 of Figure 1.

Figure 4 is a view similar to Figure 2, but with a portion of the bracket and the blind members shown detached and removed from the frame opening.

The present invention is a part of the disclosure contained in my copending application Serial No. 452,657, filed July 28, 1942, which matured into Patent No. 2,335,892, on December 7, 1943, and in the present drawing I have illustrated the invention in connection with a Venetian blind of the form shown in said application. The blind as shown is mounted in a frame 5 and comprises the usual slats 6 connected together by tapes 7 and suspended by such tapes from a tilt rail 8. Above the rail 8 is positioned a head rail or member 9 through which are threaded the lifting cords 12. Below the rail 8 but above

the upper slat is a rail or bar 13 which serves as a guide for the cords which are arranged to extend through such bar to the bottom tilt rail (not shown). For a full showing and description of the blind including the above parts, reference may be had to the application aforesaid.

The head member or rail 9 is arranged to be positioned against the upper side 14 of the frame 5 and may be held in place by means of screws 16 extending through the member and into the side 14.

For supporting the tilt rail 8, there is provided at each of the sides 17 of the frame a bracket 18, such brackets being formed to provide bearings for the journals 19 provided at the opposite ends of the rail. The brackets are of a novel form and are so designed as to permit the easy insertion in, or withdrawal of the journals from, the bearings by a simple removal and replacement of a part of the bracket.

As will be seen from the drawing each of the brackets are formed of two sections 21 and 22, which may be of wood or the like and are arranged for positioning on the sides 17 preferably directly under the member 9. The sections 21 and 22 are arranged to be held in juxtaposition and are formed with sides 23 and 24 respectively, which interengage one another when the sections are operatively held in association. The sides 23 and 24 are each formed with angularly related upper and lower portions, the portions of the side 23 being indicated by the numerals 26 and 27, while the corresponding portions of the side 24 are indicated by the numbers 28 and 29.

At the inner or adjacent ends of the side portions 26 and 27, and the portions 28 and 29, are recesses 31 and 32 whose walls 33 and 34 are formed as continuations of the side portions of the respective sections. Each of the walls 33 and 34 are in the form of segments of substantially 180° so that when the sides 23 and 24 are interengaged in operative relation, the walls 33 and 34 will provide a cylindrical bearing for the tilt-rail journals. The sections are arranged to be held in place with the side portions 26 and 28 vertically disposed and with the section 21 adjacent what may be the outer side of the frame opening. Attachment of the sections 21 and 22 in position, may be effected by means of screws 36 and 37 respectively, the section 21 being arranged for relatively permanent attachment, while the section 22 is designed for attachment permitting relatively quick and easy release of the section. For this reason but a minimum number 55 of screws 37 are used for securing the section

22 in place. As will be clearly seen from Figures 3 and 4, the wall 33 is extended at the bottom slightly forwardly beyond the vertical center line of the arc circle so that the section 21 may form the main support for the journal temporarily without the help of section 22. The portion 21 of section 21 is at an obtuse angle to the portion 26, thus providing for ample material under the bottom of wall 33, and at the same time providing a guide surface for the rail journal in moving the latter into or out of the recess. Preferably the side portion 26 is located somewhat rearwardly of the center of the arc circle aforesaid so that notwithstanding the extension of the recess wall at the bottom, the arc of the walls of each section may be substantially 180°.

The rail or bar 13 is arranged to be releasably supported in brackets 41 fixed to the sides 17 of the frame and are provided with recesses 42 in which the ends of the rails are seated. The upper side of the recesses are open to permit the insertion or withdrawal of the bars from the brackets, and in order to permit the insertion or removal of the bars through the frame, the bottom of the brackets 18 and the top of the brackets 41 are spaced sufficient to permit the passage of the bars therebetween.

With all of the parts of the blind in position as shown in Figure 1, should it be desired to remove the blind from the opening for repair or other reasons, it is merely necessary to release the screws 16 from the frame, withdraw the screws 37 sufficient to release the sections 22 and then detach such sections, and then lift the rail 13 from the recess 42. The blind may then be moved as a unit forwardly through the frame opening, as shown in Figure 4. To replace the

blind in the frame the parts are moved back into their operative positions in the frame or brackets and the head member and sections 22 secured back into place. Preferably sections 21 and 22 are positioned to lie sufficiently below the head member to permit the latter to be readily fitted into or removed from position under the frame top.

I claim:

10. 1. In a bracket for supporting a journal of a tilt rail of a Venetian blind, a pair of separable sections having interengaging sides with a complementary angularly related portion provided at their juncture with recesses defining together a substantially cylindrical bearing for the rail journal, means to relatively permanently fix one of said sections, the other section being releasably held in operative position relative to the first section.
15. 2. In a bracket for supporting a journal of a tilt rail of a Venetian blind, a pair of separable sections having interfitting sides provided with complementary angulated portions with recesses at the inner ends of said portions, said recess having semi-circular walls contiguous with said portions and providing a cylindrical bearing for said journal, each of said sections having one of said interfitting sides vertically disposed and one of said sections having its angulated portion forming an obtuse angle with its said vertical side, and the other of said sections having its said portion forming with its said vertical side an obtuse angle complementary to said first obtuse angle, the section with the second angle being releasably mounted in operative position relative to the other section.

CHARLES H. WOOD.
